CONTAINER AND CLOSURE RETAINER
THEREFOR

Darrell C. Crain, Washington, D. C.

Application February 14, 1934, Serial No. 711,253

6 Claims. (Cl. 221—60)

This invention relates to containers of the type having an opening provided with a cap or closure, and more particularly to retainers for preventing loss of the closure when removed from the container.

Various forms of closure retainers have been proposed for use with the small collapsible containers in which such materials as tooth paste, shaving cream, paint and the like are sold. Some of the proposed constructions have been impractical from the standpoint of cost and others are open to the objection that the retainer interferes with the ready removal and replacement of the closure. Retainers which provide a relatively fixed support for the closure are usually of such construction that free access to the container opening is obstructed, while the flexible chain type of retainer which permits the closure to be moved clear of the opening may be so bent or looped as to make it difficult to apply or remove the closure.

An object of the present invention is to provide a container which includes a removable closure, usually of the threaded cap type, and a simple and efficient retainer for preventing loss of the closure. An object is to provide a container having a nozzle or opening that may be closed by a removable closure, and a retainer in which the closure is loosely mounted for such movement as is necessary for the removal and replacement of the closure, the retainer being mounted on the container for pivotal movement about an axis which is not coincident with the axis of the nozzle, whereby the retainer may be turned to move the closure away from the nozzle after the closure is released.

A further object is to provide a container having a laterally offset nozzle or opening arranged at an angle, which may be and preferably is a right angle, to the axis of the container, a closure for the nozzle, and a retainer mounted for pivotal movement about the axis of the container and having an extension in which the closure is loosely mounted; the arrangement of the parts being such that the retainer may be turned to move the closure away from the nozzle or alternatively to position the closure in alignment with the nozzle.

A further object is to provide an attachment which may be employed with a collapsible tube and threaded closure of the usual and familiar construction; the attachment including an elbow having one end for connection to the container in place of the usual closure and an outer end for receiving the threaded closure, and a retainer which is pivotally mounted on the container by the elbow member, the retainer having an extension in which the closure may be mounted.

These and other objects and advantages of the

invention will be apparent from the following specification when taken with the accompanying drawing, in which:

Fig. 1 is a perspective view of a container provided with a closure and closure retainer constructed in accordance with the invention;

Fig. 2 is a fragmentary side elevation of the same, with parts in section, the closure being released from but aligned with the nozzle;

Fig. 3 is a plan view of the container, an open position of the closure being shown in dotted lines;

Fig. 4 is a fragmentary side elevation of another form of closure retainer; and

Fig. 5 is a side elevation of an attachment for applying the invention to collapsible tubes of the customary type.

In the drawing, the reference numeral 1 identifies a collapsible tube container provided with a threaded nozzle 2 which, in the customary tube constructions, receives an internally threaded cap or closure. In accordance with the invention, a bent outlet tube or elbow 3 is threaded upon the nozzle 2 to form a spout having an outlet end 4 which is laterally offset from the container end 25 of the outlet tube 3, the preferred construction being such that the axis of the outlet 4 is inclined to the axis of the container nozzle 2. One end 5 of a retainer strap is apertured to fit over the tube nozzle 2 and it is held in place on the tube by the spout or elbow 3. The other end of the retainer strap is bifurcated to form notched spring fingers 6, 6 in which the closure 7 is loosely mounted to permit rotation of the closure.

The length of the threaded lower end of the elbow 3 is such that the retainer strap is free to turn about the axis of the tube 1 when the closure is unscrewed from the threaded end 4 of the elbow. The closure may therefore be moved angularly to clear the elbow outlet, as shown in dotted lines in Fig. 1, when the closure is unscrewed. The pivoted end 5 of the retainer has, however, a fairly snug fit between the top of the container and the lower face of the elbow 3. The advantage of a relatively firm pivotal mounting 45 of the retainer strap on the container is that the closure 7 will be supported at the proper elevation to engage the threaded end when the strap is so turned as to bring the closure into horizontal alignment with the elbow outlet. This 50 automatic vertical alignment of the closure is obtained since the retainer strap is relatively rigid so far as concerns any relative vertical displacement of the opposite ends 5 and 6 of the retainer.

The retainer strap may be relatively flexible in other directions and, as shown in Figs. 1 and 2, the strap is formed of resilient or spring metal and the intermediate portion 8 is reversely bent to form a spring hinge to facilitate relative an-

- 5 gular movement of the opposite ends of the strap. Such flexing is necessary when the spring fingers 6 are seated in a groove 9 of the closure which is too short to allow substantial axial movement of the closure in the retainer strap. The normal or unstressed position of the spring retainer strap is preferably such that the closure will be spaced slightly from the end 4 of the outlet tube when the closure is unscrewed from the tube.
- 10 Except where impractical in the case of containers of comparatively small diameter, the lateral extension of the elbow 3 will preferably be made so short that no portion of the closure 7 projects beyond the outline of the container 1, 15 see Fig. 3, and containers embodying the invention may therefore be packed in cartons of the same size as those used with collapsible tubes having the customary end caps.

It is not essential that the container be formed 20 with the customary axial nozzle 2 as the elbow or bent spout 3' may be a part of the tube, as shown in Fig. 4. The retainer is accurately positioned and pivotally mounted on the lower portion of the elbow nozzle 3' in any suitable manner, for example by providing the elbow with a 25 circumferential groove 10 for receiving the spring fingers 5' of the retainer. The particular retainer shown in Fig. 4 is formed of wire and includes a spring loop 6' for receiving the closure and an 30 intermediate spring portion 8', but it will be apparent that the retainer for use with this integral spout type of container could be a metal strap similar to that shown in Fig. 1.

Another form of the invention, as illustrated 35 in Fig. 5, comprises an elbow or bent spout 13 having its lower end 14 threaded for attachment to the usual container nozzle, the lower edge of the end 14 being cut back to provide a hub on which the end of the retainer strap 15 is pivotally 40 mounted when the spout is secured to the container. The retainer strap differs from that shown in Figs. 1 and 2 in that it is a substantially rigid angle strap, since the fingers 16 of the retainer engage in a relatively long groove 19 that 45 allows for the required longitudinal movement of the closure 7'. Alternatively, this longitudinal movement may be taken up in the case of a rigid retainer by slotting the pivoted end 15 to permit the strap to slide on the hub 14 of the 50 elbow 13.

It will be noted that the retainer preserves the same general shape or configuration whether the cap is threaded upon the container or is free. There is some slight change of shape in the case 55 of the resilient retainers of Figs. 1 to 4, but this small variation is to be distinguished from the operation of flexible chain retainers and of U-shaped springs that tend to assume an angular form when the cap is freed from the container. 60 For convenience of description, the retainers contemplated by this invention may be distinguished from the prior constructions by the statement that, whether of the relatively rigid or of the relatively flexible type, the retainer has a "substan- 65 tially permanent shape".

The novel retainers may be combined with the tube and closure in the manufacture of the containers or, alternatively, the bent spout and retainer may be separately manufactured for later 70 application to a tube and closure. When the customary closure of a standard tube is so shaped that it may be mounted in the retainer, it will not be necessary to include the closure in the

equipment for applying the invention to the customary collapsible tubes.

The invention is particularly useful in connection with collapsible tubes but may be applied to other types of containers where it is 5 desirable to prevent loss of a removable closure. The invention is not restricted to the particular constructions herein illustrated and described, and numerous changes may be made in the design and construction of the several parts with- 10 out departure from the spirit of my invention.

I claim:

1. A container having an outlet tube terminating in an outlet end laterally offset from the container end of said tube, a closure for said outlet 15 end, a closure retainer of substantially permanent shape and having one end in which said closure is loosely mounted, and means supporting the other end of said closure retainer for pivotal movement about the axis of the container end of 20 said outlet tube, whereby said retainer may be turned to move said closure away from the outlet end of said tube after the closure is loosened therefrom.

2. A container having a bent outlet tube terminating in a threaded outlet end laterally offset from and inclined to the container end of said tube, a closure for said outlet end, and a retainer of substantially permanent shape having one end supported for pivotal movement in a plane substantially normal to the axis of the container end of said outlet tube, the other end of said retainer comprising means supporting said closure for rotation about substantially the axis of said outlet end when said retainer is positioned to align said 35 closure with said outlet end of said tube.

3. A collapsible container having an axially arranged nozzle, a bent spout secured to said nozzle and having an outlet end laterally offset therefrom, a closure for the outlet end of said spout, 40 and a closure retainer having one end portion in which said closure is loosely mounted and a second end portion fitting over said container nozzle, whereby said closure retainer is pivotally mounted on said container nozzle, said bent spout 45 overlying and normally retaining said second end portion of said closure retainer in place on said container nozzle.

4. The invention as claimed in claim 3, wherein the intermediate portion of said closure retainer 50 is flexible to facilitate relative angular movement of the end portions of said closure retainer.

5. The invention as claimed in claim 3, wherein the first end portion of said closure retainer comprises a pair of clamping fingers, and said closure 55 has a circumferential groove in which said fingers are seated, the groove having a length equal to the longitudinal movement of the closure during attachment to or removal from said bent spout.

6. A closure retainer attachment for use with a collapsible tube of the type having a threaded nozzle and a closure therefor, said attachment comprising an elbow spout having one end threaded for connection to the nozzle of a tube and a threaded outlet end laterally offset from said first 60 end, and a retainer of substantially permanent shape having one end apertured to fit over and pivotally mount said retainer on a tube nozzle, the other end of said retainer comprising means for loosely supporting a closure for the threaded 65 outlet end of said elbow spout.
